(57)

CLAIM

The ornamental design for luggage, as shown and described.

DESCRIPTION

FIG. 1 shows a front perspective view of luggage;
FIG. 2 shows a front elevation view of the luggage of FIG. 1;
FIG. 3 shows a rear elevation view of the luggage of FIG. 1;
FIG. 4 shows a left elevation view of the luggage of FIG. 1;
FIG. 5 shows a right elevation view of the luggage of FIG. 1;
FIG. 6 shows a top view of the luggage of FIG. 1; and,
FIG. 7 shows a bottom view of the luggage of FIG. 1.
The dash-dot-dash broken lines immediately adjacent the claimed surfaces represent boundaries of the claimed design.
The dash-dash broken lines depict unclaimed portions of the luggage. The broken lines form no part of the claimed design.
